(57) **CLAIM**

The ornamental design for a hair dryer, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front, right side perspective view of a first embodiment of a hair dryer, showing my new design;

FIG. 2 is a rear, left side perspective view thereof;

FIG. 3 is a right side view thereof;

FIG. 4 is a left side view thereof;

FIG. 5 is a front view thereof;

FIG. 6 is a rear view thereof;

FIG. 7 is a top plan view thereof;

FIG. 8 is a bottom plan view thereof;

FIG. 9 is a front, right side perspective view of a second embodiment of the hair dryer, which differs from the first embodiment only in the color of the front part of the hair dryer;

FIG. 10 is a front view of a third embodiment of the hair dryer, which differs from the first and second embodiments only in the color of the front part of the hair dryer; and,
FIG. 11 is a front, left side perspective view of a fourth embodiment of the hair dryer, which differs from the first, second and third embodiments only in the color of the front part of the hair dryer.

The broken lines in the figures illustrate portions of the hair dryer that form no part of the claimed design.
